Patented Dec. 18, 1917.

UNITED STATES PATENT OFFICE.

HARRY N. BELL, OF INDIANAPOLIS, INDIANA.

VENDING-MACHINE.

1,250,544.

Specification of Letters Patent. Patented Dec. 18, 1917.

Application filed March 7, 1917. Serial No. 152,987.

To all whom it may concern:

Be it known that I, HARRY N. BELL, a citizen of the United States, residing at Indianapolis, in the county of Marion and State of Indiana, have invented a new and useful Vending-Machine, of which the following is a specification.

It is the object of my invention to provide a coin-controlled vending machine of simple and compact construction, which is fool-proof, which cannot be "beat", which prevents insertion of additional coins during operation by one coin, and which is automatically locked against further operation and further reception of coins upon the exhaustion of the supply of vendible commodity.

The apparatus shown in the drawings has been primarily designed for mounting on comparatively narrow supports, such as window casings, and for the purposes of dispensing chewing gum, although it is not limited to this mounting or this purpose.

The accompanying drawing illustrates my invention.

Figure 1 is a front elevation of a vending machine embodying my invention, on a reduced scale; Fig. 2 is also a front elevation of such machine, but with the face plate removed and on a full-size scale; Fig. 3 is a vertical section on the line 3—3 of Fig. 2; Fig. 4 is a transverse section on the line 4—4 of Fig. 3; Fig. 5 is a transverse section on the line 5—5 of Fig. 2, with the operating plunger in normal position and with a coin in place; Fig. 6 is a view similar to Fig. 5, but with the operating plunger pushed in and the coin tilted; Fig. 7 is a partial vertical section on the line 7—7 of Fig. 4; and Fig. 8 is a partial vertical section corresponding to the lower portion of Fig. 3, but with the discharge cylinder in position so that its discharge slot receives an article to be discharged.

The vending machine comprises a main casing 15 providing back, side walls, top, and bottom, and a front face plate 16 hinged at the bottom thereof and provided with any suitable locking device 14 at the top to lock it in closed position. At the lower end, the face plate 16 is provided with a cut-away portion 17 to allow the insertion of the finger of a customer and the removal of the article bought by him. The face plate may also be provided with a window 18 to permit the contents of the machine to be seen.

A vertical partition 20 parallel to the back of the casing 15 extends from the top down nearly to the bottom, to provide a chamber between it and such back for a lever 21 mounted on a pivot 22, said lever being spring-pressed in a clockwise direction (Fig. 2) by a spring 23. Below the lower end of the partition 20 is mounted a discharge cylinder 25, pivoted on a transverse horizontal axis on trunnions 26 supported in one side wall of the casing 15 and in a partition 27 paralleling but slightly spaced from the other side wall, said last partition and side wall forming between them a vertical passage 28 for the discharge of undersized coins, as explained more fully hereinafter. The discharge cylinder 25 has a flat discharge groove 29, for receiving the bottom one of a pile of articles 30 to be dispensed when the discharge cylinder is moved to the position shown in Fig. 8, and to carry such article from the bottom of such pile when the cylinder is moved to the position shown in Fig. 3 and discharge it downward past the front edge of a horizontal partition 31 into a discharge chamber 32 from which it can be removed through the cut-away portion 17 of the face plate by the insertion of the purchaser's finger. The partition 31 prevents tampering with the lever 21. The lower end of this lever 21 is provided with a pin 33 which projects into a helical slot 34 on the surface of the discharge cylinder 25, so that by the operation of such lever the discharge cylinder 25 may be moved to either the position shown in Fig. 3 or that shown in Fig. 8. Either position may be the normal position, depending upon whether the slot 34 is a right hand or a left hand helix. In the arrangement shown, the position shown in Fig. 3 is the normal position, so that when the lever 21 is moved in a counterclockwise direction (Fig. 2) against the spring 23 the discharge cylinder 25 is turned from the position shown in Fig. 3 to the position shown in Fig. 8, and when such lever is allowed to move in a clockwise direction under the action of the spring 23 the discharge cylinder 25 is turned from the position shown in Fig. 8 to the position shown in Fig. 3. At that end of the slot 34 in which the pin 33 is located when the lever 21 is in normal position (as shown in Fig. 2) such slot is provided with a reverse portion 35, which interlocks with the pin 33 to prevent operation of the device without a

coin by manipulation of the discharge cylinder 25; that is, by reason of this reverse portion, it becomes impossible to turn the discharge cylinder 25 by reaching in through 5 the cut-away portion 17.

At the top, on the right hand side as shown in Fig. 2, there is a coin-receiving chute 40 which extends through the face plate 16. This chute is barely large enough to receive 10 a coin of the desired size, so that a larger coin cannot enter. The rear end of the floor 41 of this chute is spaced from a stop portion 42 on the back of the casing 15 a very slight amount less than the diameter of the 15 desired operating coin, as is clear from Fig. 7, so that any smaller coin will fall through the space thus provided and pass down through the passage 28 into the chamber 32, from which the depositor can withdraw it. 20 A coin 43 of the desired size is caught between this stop 42 and the rear end of the floor 41, as is clear from Fig. 7, in which position its front edge is behind a lug 44, as is clear from Figs. 3 and 5, and its rear edge 25 is in the plane of the lever 21, the upper end of which is enlarged so as to have guiding surfaces on both the front face of the back of the casing 15 and the rear face of the partition 20. The intermediate part of this 30 coin 43 is opposite the inner end of a plunger 45 mounted in a boss on the right hand side of the casing 15 near the top, which plunger is spring-pressed outwardly by a spring 46, so that when this plunger 45 is pushed in the 35 coin acts as a lever of a third class with the lug 44 as the fulcrum and pushes the upper end of the lever 21 to the left (as indicated in Fig. 6), so as to operate the discharge cylinder 25. With the slot 34 in the direction shown, this causes the discharge cylinder 40 25 to be moved from the position shown in Fig. 3 to the position shown in Fig. 8, and when this latter position is reached the pile of articles 30 drops so that the lower 45 one of them is in the groove 29. Directly after this the rear edge of the coin 43 swings clear of the upper end of the lever 21 and escapes into the upper compartment 47, the floor of which is provided by a cross partition 48 above the pile of vendible articles 30. Upon such escape of the coin, the spring 23 throws the lever 21 back to normal position, thereby moving the discharge cylinder 25 into position to discharge the purchased article into the chamber 32. When 55 a coin 43 is not in place, the plunger 45 may freely be pushed in without producing any operation. The coin-engaging face of the lever 21 is curved as shown to allow the coin 60 to swing clear of it when the lever reaches a definite position, and is provided with small shoulders or roughenings 49 which when an operation is started prevent backward movement of the lever until the coin-produced 65 movement is completed. During this coin-

produced movement, the lower edge of the coin rides on a shelf 55.

A lever 50 is mounted in ears 51 in the upper part of the casing 15, and at its front end is provided with a finger 52 which may 70 swing into the coin chute 40 so as to prevent the insertion of coins into such chute. This lever is spring-pressed into position to do this, by a spring 53 acting on its rear end. However, a downwardly projecting finger 54 75 at the rear end of this lever 50 is in the path of the upper end of the lever 21, so that when such lever 21 is swung to its normal position its upper end engages the finger 54 at the rear end of the lever 50 and pushes such 80 lever against the action of the spring 53 so as to remove the finger 52 from the coin chute 40. By this means, a coin cannot be inserted in the coin chute 40 during the operation of the device following the previous 85 insertion of a coin, for the finger 52 enters the chute 40 as soon as the lever 21 begins to move from its normal position.

In order to prevent coins from being inserted in the chute 40 when the pile 30 has 90 been exhausted, the weight 60 which is placed on the top of such pile to force it downward is provided with a depending latch 61 at one side. When the articles 30 have all been discharged, this weight 60 95 rests directly on top of the discharge cylinder 25, and the latch 61 projects over the end of such cylinder into the path of a pin 62 on such end, so as to prevent the cylinder 25 from returning completely to normal position, thereby also holding the lever 21 from returning completely to normal position and allowing the finger 52 to remain projected into the chute 40 so as to prevent the insertion of coins therein until the machine has 100 been re-charged with vendible articles.

I claim as my invention:

1. In a vending machine, the combination of a discharge cylinder mounted for oscillation, an operating lever, said lever being 110 provided with a pin and said discharge cylinder with a helical slot into which said pin projects whereby operation of the lever produces oscillation of the discharge cylinder, that end of said slot in which said pin 115 is normally located being provided with a reverse portion for preventing manipulation of the discharge cylinder, a manually movable operating member, and a coin chute for receiving a coin and conducting it into 120 position to provide an operating connection between said operating member and said operating lever.

2. In a vending machine, the combination of a discharge cylinder mounted for oscillation, an operating lever, said lever being 125 provided with a pin and said discharge cylinder with a helical slot into which said pin projects whereby operation of the lever produces oscillation of the discharge cylinder. 130

der, a manually movable operating member, and a coin chute for receiving a coin and conducting it into position to provide an operating connection between said operating member and said operating lever.

3. In a vending machine, the combination of a discharge cylinder mounted for oscillation, an operating lever, said lever being provided with a pin and said discharge cylinder with a helical slot into which said pin projects whereby operation of the lever produces oscillation of the discharge cylinder, a spring tending to move said lever to a normal position at one limit of its movement, that end of said slot in which said pin is located when the lever is at such limit of movement being provided with a reverse portion for preventing manipulation of the discharge cylinder, a manually movable operating member, and a coin chute for receiving a coin and conducting it into position to provide an operating connection between said operating member and said operating lever whereby operation of said operating member moves said operating lever away from such normal position.

4. In a vending machine, the combination of a discharge cylinder mounted for oscillation, an operating lever, said lever being provided with a pin and said discharge cylinder with a helical slot into which said pin projects whereby operation of the lever produces oscillation of the discharge cylinder, a spring tending to move said lever to a normal position at one limit of its movement, a manually movable operating member, and a coin chute for receiving a coin and conducting it into position to provide an operating connection between said operating member and said operating lever whereby operation of said operating member moves said operating lever away from such normal position.

5. In a vending machine, the combination of a discharge cylinder mounted for oscillation, an operating lever, said lever being provided with a pin and said discharge cylinder with a helical slot into which said pin projects whereby operation of the lever produces oscillation of the discharge cylinder, a manually movable operating member, a coin chute for receiving a coin and conducting it into position to provide an operating connection between said operating member and said operating lever, and an obstructing device for preventing the insertion of coins in said slot, said obstructing device being associated with said operating lever so that it is inoperative when said operating lever is in normal position but is operative when such lever is out of such normal position.

6. In a vending machine, the combination of a discharge cylinder mounted for oscillation, an operating lever, said lever being

provided with a pin and said discharge cylinder with a helical slot into which said pin projects whereby operation of the lever produces oscillation of the discharge cylinder, a spring tending to move said lever to a normal position at one limit of its movement, a manually movable operating member, a coin chute for receiving a coin and conducting it into position to provide an operating connection between said operating member and said operating lever whereby operation of said operating member moves said operating lever away from such normal position, and an obstructing device for preventing the insertion of coins in said slot, said obstructing device being associated with said operating lever so that it is inoperative when said operating lever is in such normal position but is operative whenever such lever is out of such normal position.

7. In a vending machine, the combination of a discharge cylinder mounted for oscillation, an operating lever, said lever being provided with a pin and said discharge cylinder with a helical slot into which said pin projects whereby operation of the lever produces oscillation of the discharge cylinder, a manually movable operating member, a coin chute for receiving a coin and conducting it into position to provide an operating connection between said operating member and said operating lever, an obstructing device for preventing the insertion of coins in said slot, said obstructing device being associated with said operating lever so that it is inoperative when said operating lever is in normal position but is operative when such lever is out of such normal position, a member for pushing the vendible articles toward said discharge cylinder, and a latch on said pushing member for locking said discharge cylinder to prevent the return of the operating lever to normal position when the supply of vendible articles is exhausted.

8. In a vending machine, the combination of a discharge cylinder mounted for oscillation, an operating lever, said lever being provided with a pin and said discharge cylinder with a helical slot into which said pin projects whereby operation of the lever produces oscillation of the discharge cylinder, a spring tending to move said lever to a normal position at one limit of its movement, a manually movable operating member, a coin chute for receiving a coin and conducting it into position to provide an operating connection between said operating member and said operating lever whereby operation of said operating member moves said operating lever away from such normal position, an obstructing device for preventing the insertion of coins in said slot, said obstructing device being associated with said operating lever so that it is inoperative when said operating lever is in such normal position.

4
position but is operative whenever such lever is out of such normal position, a member for pushing the vendible articles toward said discharge cylinder, and a latch 5 on said pushing member for locking said discharge cylinder to prevent the return of the operating lever to normal position when the supply of vendible articles is exhausted.

9. In a vending machine, the combination 10 of a discharge cylinder mounted for oscillation, an operating lever, said lever being provided with a pin and said discharge cylinder with a helical slot into which said pin projects whereby operation of the lever produces oscillation of the discharge cylinder, a manually movable operating plunger, and a coin chute for conducting a coin into position for coöperation with said operating lever and said operating plunger, said coin 15 chute being provided with a lug which serves as a fulcrum against which one part of the coin bears and said operating plunger and operating lever respectively engaging other parts of the coin so that by pushing 20 in the plunger the coin acts as a lever connecting the plunger and operating lever.

10. In a vending machine, the combination 30 of a discharge cylinder mounted for oscillation, an operating lever, said lever being provided with a pin and said discharge cylinder with a helical slot into which said pin projects whereby operation of the lever produces oscillation of the discharge cylinder, a manually movable operating plunger, and a coin chute for conducting a coin into 35 position for coöperation with said operating lever and said operating plunger, said coin chute being provided with a lug which serves as a fulcrum against which the coin 40 bears near one edge and said operating plunger and operating lever respectively engag-

ing the coin at an intermediate portion and near the opposite edge so that by pushing in the plunger the coin acts as a lever of the third class connecting the plunger and 45 operating lever.

11. In a vending machine, the combination 50 of discharge mechanism, an operating lever for operating such discharge mechanism, a manually movable operating plunger, and a coin chute for conducting a coin into position for coöperation with said operating lever and said operating plunger, said coin chute being provided with a lug which serves as a fulcrum against which one part 55 of the coin bears and said operating plunger and operating lever respectively engaging other parts of the coin so that by pushing in the plunger the coin acts as a lever connecting the plunger and operating lever. 60

12. In a vending machine, the combination 65 of discharge mechanism, an operating lever for operating such discharge mechanism, a manually movable operating plunger, and a coin chute for conducting a coin into position for coöperation with said operating lever and said operating plunger, said coin chute being provided with a lug which serves as a fulcrum against which the coin 70 bears near one edge and said operating plunger and operating lever respectively engaging the coin at an intermediate portion and near the opposite edge so that by pushing in the plunger the coin acts as a lever of the third class connecting the plunger 75 and operating lever.

In witness whereof I have hereunto set my hand at Indianapolis, Indiana, this fifth day of March, A. D., one thousand nine hundred and seventeen.

HARRY N. BELL.
